C. D. SMITH,
PHONOGRAPH REPRODUCER AND RECORD THEREFOR,
APPLICATION FILED NOV. 6, 1916.

1,260,586.

Patented Mar. 26, 1918.

UNITED STATES PATENT OFFICE.

CHARLES D. SMITH, OF SAN JOSE, CALIFORNIA, ASSIGNEE OF ONE-HALF TO HENRY T. WELCH, OF SAN JOSE, CALIFORNIA.

PHONOGRAPH-REPRODUCER AND RECORD THEREFOR.

1,260,586.

Specification of Letters Patent. Patented Mar. 26, 1918.

Application filed November 6, 1916. Serial No. 129,782.

To all whom it may concern:

Be it known that I, CHARLES D. SMITH, a citizen of the United States, and resident of San Jose, in the county of Santa Clara and State of California, have invented certain new and useful Improvements in Phonograph-ducers and Records Therefor, of which the following is a specification.

My invention relates to a phonograph reproducer and the record therefor, and the object of my invention is to provide a phonograph reproducer and record that will produce sounds of greater volume and carrying power than those now in general use. Another object is to provide a mechanism by which imperfections in the recording and reproducing of one half of the device may be rendered less noticeable by the other half of the device.

With the above and other objects in view, the invention consists in the novel and useful provision, formation, construction, combination and relative arrangement of parts as hereinafter described, shown in the drawings and finally pointed out in the claims.

In the drawings:—

Figure 1 is a side elevation of my invention, a part of the record being broken away.

Fig. 2 is an edgewise view of my invention, one half being in section.

Fig. 3 is a side elevation of the sound diverting plate.

Fig. 4 is a plan view of the record with a portion of the parallel grooves omitted.

Fig. 5 illustrates a sound box embodying my invention in which the diaphragms are placed parallel to each other.

Fig. 6 is a detail elevation of a needle with a double, shank adapted for use in my improved reproducer.

Similar characters of reference refer to similar parts throughout the several views.

Referring now more particularly to the drawings, 1 indicates a circular V shaped sound box having a diaphragm 2 fitted in each side thereof in the manner usual in the construction of such devices. A vibrating stem 3 is connected at one end to each diaphragm by means of a threaded pin 3^a securely fastened to said diaphragm and passing through the end of said stem and held securely to said stem by nuts 3^b screwed onto pin 3^a, one on each side of said stem 3. The other end of stem 3 is fitted with

a socket 4 adapted to receive needle 5 which is held in position by set screw 6. The upper portion of stem 3 is bent so as to parallel the surface of diaphragm 2 but is bent inwardly toward the lower end thereof as 60 at 7 to form an arm lying substantially perpendicular to the diametrical median plane of sound box 1 and by which it is secured to spring 8 by screws 9, spring 8 being secured to the lowermost portion of 65 the circumference of sound box 1. A chisel edged fulcrum may be introduced at 8^a if desired. The lowermost portion of stem 3 in which is formed socket 4 is formed and adjusted to lie in a plane substantially parallel with a diametrical plane passing through said drum midway between said diaphragms 2. At 10 is shown a sound plate provided with an orifice 11. At 12 is shown a sound diverting plate circular in form 70 and completely separating the two halves of sound box 1. Plate 12 is hollowed out on each side from a point below the center thereof to the outer circumference as shown at 13. At 14 is provided an opening in the 75 upper surface of sound box 1 to which is attached sound conveyer 15. A second and smaller tube 16 is connected to the lower end of conveyer 15 as indicated at 17, or directly to any point on the circumference of sound 80 box 1 as indicated in dotted lines at 18. At 19 I have shown a double cut disk record adapted to be operated upon simultaneously by needles 5—5. Each of the two grooves 85 20 is an exact, but reversed, counterpart of 90 the other, consequently when the device is in operation the two diaphragms 2 are acted upon simultaneously and receive exactly 95 the same vibration but in opposite directions.

The sound waves thrown off by diaphragms 2 pass through orifices 11 and are diverted upwardly by plate 12 until they join and augment each other at opening 14 and pass through sound conveyer 15 to the 100 point of discharge. The volume of sound emitted by a double reproducer of this kind is practically double that of the single reproducer and therefore is desirable for use in large halls for concerts, entertainments, etc. 105 In order to increase the carrying qualities of said augmented sounds air under pressure and in desired quantities is forced through tube 16 into sound box 1 or sound conveyer 15 from any suitable source of supply as 110

indicated at 16^a, the quantity being governed by the pressure applied thereto and by valve 21.

The two nuts 3^b permit a very accurate adjustment of stem 3 so as to provide the proper tension of diaphragm 2 and the precise positioning of needles 5. The device hereinbefore described is designed for use with a record having grooves provided with 10 a laterally undulatory surface, but it is understood that changes may be made to adapt the invention for use on a record provided with grooves having a vertically undulatory surface.

15 In operating my improved phonograph, if one of grooves 20 is imperfect in any respect or at any point or points, and as a consequence one of said diaphragms 2 transmits an imperfect vibration and as a result 20 an imperfect sound wave reaches sound conveyer 15, then this wave is met by a perfect wave transmitted by the opposite diaphragm and a more perfect wave is consequently discharged from conveyer 15, since a perfect 25 wave from one diaphragm would naturally render an imperfect wave from the other diaphragm less noticeable. As a result of this dual construction an even, smooth succession of sounds of great volume are 30 discharged by sound conveyer 15.

It is my desire to cover broadly a double sound box and record of the character described and either a single or double sound box provided with an air inlet as described, 35 therefore I do not wish to confine myself to the specific mechanism herein shown and described but to make such alterations and changes in form, construction and operation as may be necessary to meet exigencies of 40 practical application and manufacture and within the scope of the appended claims. For instance, plate 13 may be made in the form indicated in dotted lines at 22 and may form a part of sound plate 10, or the diaphragms 2 may be placed parallel to each 45 other as indicated in Fig. 5 in which the circular sound box is indicated by 1^a.

Having thus described my invention, what I claim as new and desire to secure by Letters Patent, is:—

1. In a phonograph, a reproducer comprising a pair of opposed, coöperating sound

reproducers having a sound conveyer common to both of them and independently operating means for producing simultaneous and equal opposed vibrations in each of them. 55

2. In a phonograph, a reproducer comprising a pair of opposed, coöperating sound reproducers having a sound conveyer common to both of them and means for producing simultaneous and equal opposed vibrations in each of them, said means comprising a revolving record having a pair of reversed duplicate sound record grooves 60 formed therein, each of said grooves being adapted to coöperate with one of said pair of opposed coöperating sound reproducers. 65

3. In a phonograph, the combination with a record having a pair of reversed duplicate 70 sound record grooves formed therein, of a reproducer provided with a pair of opposed coöperating diaphragms each diaphragm having a stylus operatively attached thereto, and each stylus being independently mounted on said reproducer and adapted to operate in one of said grooves. 75

4. A phonograph reproducer comprising a sound box having a sound conveyer attached thereto, a sound diverting plate positioned in the diametrical median plane thereof, a pair of opposed coöperating diaphragms positioned therein, one on each side of said sound diverting plate, and independently operating means for imparting simultaneous and equal opposed vibrations 80 to said diaphragms. 85

5. In a phonograph, a reproducer comprising a pair of opposed coöperating sound reproducers having a sound conveyer common to both of them, and independently operating means adjustably connected to said opposed coöperating sound reproducers for producing simultaneous and equal opposed sound vibrations in each of them. 90 95

6. The combination of a double phonograph reproducer and a record having a pair of reversed duplicate sound record grooves formed therein. 25

In testimony whereof I have hereunto affixed my signature this 27th day of October, 1916. 10

CHARLES D. SMITH.
